CLAIM

The ornamental design for seat, as shown and described.

DESCRIPTION

FIG. 1 is a right front perspective view a seat;

FIG. 2 is a front view of the seat of FIG. 1;

FIG. 3 is a back view of the seat of FIG. 1;

FIG. 4 is a left side view of the seat of FIG. 1;

FIG. 5 is a top view of the seat of FIG. 1; and,

FIG. 6 is a bottom view of the seat of FIG. 1.

The dash-dash lines in FIGS. 1-3 and 5-6 represent portions of the seat that form no part of the claimed design. The dash-dot broken lines in the figures illustrate unclaimed boundaries of the claimed design and form no part of the claimed design.
